UNITED STATES PATENT OFFICE

130,328

DESIGN FOR A COOKIE JAR OR SIMILAR ARTICLE

Charles E. Murphy, Red Wing, Minn., assignor to
The Red Wing Potteries, Inc., Red Wing, Minn., a corporation

Application September 5, 1941, Serial No. 103,171

Term of patent 3½ years

To all whom it may concern:

Be it known that I, Charles E. Murphy, a citizen of the United States of America, residing in Red Wing, county of Goodhue, and State of Minnesota, have invented a new, original, and ornamental Design for a Cookie Jar or Similar Article, of which the following is a specification, reference being had to the accompanying drawing, forming part thereof, wherein:

Figure 1 is a front perspective view of a cookie jar or similar article showing my new design.

I claim:

The ornamental design for a cookie jar or similar article, substantially as shown.

CHARLES E. MURPHY.
